ACID ALKYLATION OF ISOPARAFFINS

Arthur R. Goldsby, Beacon, N. Y., assignor, by
mesne assignments, to The Texas Company,
New York, N. Y., a corporation of Delaware

Application June 25, 1938, Serial No. 215,736

15 Claims. (Cl. 260—683.4)

1

This invention relates to the manufacture of motor fuels and has to do with the production of hydrocarbons of gasoline boiling range by the alkylation of paraffins with olefins. More particularly, the invention has to do with the alkylation of isoparaffins, such as isobutane, with normally gaseous olefins.

An important object of the invention is to alkylate an isoparaffin with a selected type of olefin.

Another object of the invention is to utilize a gaseous hydrocarbon mixture containing olefins and paraffins whereby an isoparaffin may be alkylated with the desired olefin.

In accordance with the invention, an unsaturated hydrocarbon mixture containing olefins of two to five carbon atoms is separated into fractions containing olefins of the same number of carbon atoms and then an isoparaffin is alkylated with these olefin fractions.

The unsaturated hydrocarbons suitable for treatment may comprise normally gaseous hydrocarbons resulting from the cracking of hydrocarbon oils or gases, the destructive hydrogenation of heavy hydrocarbons, the dehydrogenation of normally liquid or normally gaseous hydrocarbons; or, normally gaseous hydrocarbons resulting from special conversion operations, such as the synthesis of hydrocarbon oils from water gas. The isoparaffins may be normally gaseous or normally liquid, for example, isoparaffins of not substantially higher boiling range than gasoline, for example isobutane or isopentane.

The separation of the olefins may be effected by the use of selective absorbents or selective polymerizing agents, for example, an acid, such as sulfuric acid or phosphoric acid. Methods which are specifically contemplated include the selective polymerization with a solid phosphoric acid catalyst of the type, and according to the method, described in the Ipatieff Patent No. 2,101,857, December 14, 1937; and the selective absorption with sulfuric acid according to the process disclosed in the Taveau Patent No. 1,810,192, June 16, 1931. The alkylation operation is preferably conducted in the presence of sulfuric acid catalyst, in accordance with the general method disclosed in the co-pending application of Korpip-Goldsby, Serial No. 148,978, filed June 18, 1937.

The invention will be more clearly understood from the following description read in connection with the accompanying drawings, which show diagrammatic sketches of apparatus suitable for carrying out the process of the invention.

Figure 1 shows an apparatus for practicing the invention when using as a step of the process the

2

selective polymerization of the olefins by a catalyst comprising phosphoric acid to selectively polymerize the olefins. Figure 2 shows an apparatus for use in a modification of the invention wherein the olefins are selectively absorbed with sulfuric acid. The drawings are obviously diagrammatic and are subject to variations to accomplish the intended purpose of segregating the various olefins in the hydrocarbon mixture and then selectively alkylating an isoparaffin, such as isobutane, with these separated olefin fractions or polymers thereof.

Referring to Figure 1, the olefin charging stock which is preferably a hydrocarbon gaseous mixture comprising principally paraffins and mono-olefins of three and four carbon atoms is introduced from a suitable source of supply, not shown, through the line 5 in which is located a valve 6 and pump 7. The hydrocarbons are passed through a coil 9 located in a heater 10 wherein they are heated under a suitable pressure to sufficient temperatures to selectively polymerize the isobutene when contacted with a solid phosphoric acid catalyst comprising a calcined mixture of phosphoric acid, preferably pyro-phosphoric acid, and kieselguhr. The heating coil is maintained at a temperature of about 70 to 150° F., preferably about 100° F. and a pressure of 50 to 100 pounds, preferably about 100 pounds. The products are passed through the transfer line 12 to catalyst chamber 13 in which is located the catalyst. While one polymerizing chamber is shown it is to be understood that any number, connected in series or parallel, may be used. In the polymerizer 13, the isobutene is selectively polymerized, or a cross polymerization of one mol of isobutene with one mol of normal butylene is obtained. In the case of such cross polymerization, somewhat more drastic conditions of temperature and pressure than given above are desirable. The reaction products are passed from the lower portion of the catalyst chamber 13 through the valve controlled line 14 to a fractionator 15 wherein the normally liquid hydrocarbons or polymers are condensed and withdrawn from the lower portion thereof through the line 17 to be discharged from the system through the branch line 18 or delivered through the line 20 to a subsequent alkylation operation, more fully described hereinafter.

The normally gaseous hydrocarbons, after the separation of the polymers, are withdrawn from the upper portion of the fractionator 15 through the vapor line 22 and forced by the pump 23 to a coil 24 located in a heater 25. In the coil 24

the hydrocarbons are subjected to sufficient temperature and pressure to effect polymerization of the normal butylenes in the presence of phosphoric acid catalyst. The temperatures in the coil 24 may be about 150 to 250° F., preferably about 200° F., and a pressure of 150 to 350 pounds, preferably about 250 pounds. The products from coil 24 are passed through the line 23 to a second polymerizer or catalyst chamber 30 wherein they are contacted under approximately the conditions prevailing in coil 24 with solid phosphoric acid catalyst. The reaction products are transferred from the catalyst chamber 30 through the valve controlled line 31 to a fractionator 32 wherein the polymers are separated and withdrawn from the lower portion thereof through the line 33. The polymers so withdrawn may be discharged from the system through the branch line 34 or passed through the line 35 for subsequent alkylation.

The normally gaseous hydrocarbons fractionated out in the fractionator 32 should be substantially free from C₄ olefins and may contain C₃ together with lighter olefins, if any. These gases are passed from the top of fractionator 32 through the line 37 to coil 38 located in the heater 40. Pressure may be reduced on these gases by means of the valve 41 and the temperature raised in the heating coil 38 to a point such that the propylene in the gases will be polymerized in the vapor phase when contacted with solid phosphoric acid catalyst. Temperatures should be above 250° F. and may be as high as 500° F., preferably about 400 to 500° F. Pressure may range from about 100 to 300 pounds per square inch. The products are transferred from the heater through the line 342 to the polymerization chamber 43 which contains the catalyst. In the polymerization chamber the propylene is polymerized to form a large proportion of material falling within the gasoline boiling point range, for example hexenes. The polymerization products are conducted from the polymerization chamber through the valve controlled line 45 to a fractionator 46 wherein the polymers are fractionated out and withdrawn from the lower portion thereof through the line 47. Any portion of these polymers may be discharged from the system through the valve controlled line 48. It is intended, however, that the polymers be conducted through the valve controlled line 50 to be used as charge to an alkylation operation. The remaining normally gaseous hydrocarbons are discharged from the top of the fractionator 46 through the valve controlled line 52.

When operating on C₃ and C₄ hydrocarbon fractions, the gases discharged from the top of the fractionator will consist largely of propane and butanes. It may be desirable in some cases to condense a large portion of the butanes along with the final polymer withdrawn from the fractionator 46. These butanes may be utilized to impart volatility to the finished gasoline or the isobutane therein may be utilized as a portion of the isoparaffins which are alkylated in the subsequent alkylation operation. If the charging stocks contain substantial quantities of hydrocarbons of lower boiling point than C₃ hydrocarbons, for example C₂ hydrocarbons, including ethylene, it may be desirable to employ a fourth stage of polymerization in which the ethylene would be polymerized to produce an additional quantity of polymers useful as a source of olefins in the alkylation operation. By using suitable time, tem-

perature and pressure conditions, for example temperatures of 550 to 700° F., pressures above 300 pounds and a contact time of at least 300 seconds, the ethylene may be polymerized to polymers which may be used for alkylation. Such a fourth stage of polymerization is not shown on the drawing.

The polymers withdrawn through the lines 20, 35 and 58, referred to heretofore, are discharged 10 into suitable receivers or tanks 54, 55 and 56 respectively. These tanks are provided with valve controlled draw-off lines 53, 59 and 60 for charging the contents thereof to an alkylation system. For the purpose of utilizing these stocks as alkylation charges, they may be passed into the line 61 and forced by the pump 62 to an alkylation vessel 70. In this vessel the olefins are contacted with the necessary amount of isoparaffin which may be introduced through the line 65 by the pump 66, and with a suitable quantity of an acid catalyst, introduced through the line 67 by pump 68. The isoparaffin, such as isobutane, is introduced in such amount that the ratio of isobutane to olefin in the reaction mixture is in excess of 1:1 25 and preferably between about 3:1 and 5:1. The catalyst is preferably sulfuric acid of alkylation strength and preferably about 94 to 98%. The amount of acid may be 500-800% by weight based on the olefin and the major part thereof may be recycled.

30 The mixture is transferred from the vessel 70 through the line 72 to a second alkylation vessel 74. In these tanks sufficient time is provided to effect substantial alkylation of the paraffins by the 35 olefins, for example about 45 to 90 minutes and preferably about 50 to 60 minutes. The alkylation tanks are provided with means for producing as intimate contact as possible between the acid and the hydrocarbons by the use of stirrers 40 75 and 76 or other suitable mechanism. While two alkylation tanks are shown, it is to be understood that any number may be used, and the operation may be modified to use the counterflow principle for contacting the acid and the hydrocarbons, if desired. The reaction products are 45 conducted from the last alkylation tank through the line 77 to a separator 78 wherein separation is allowed to take place between the acid and the hydrocarbons. If desired, any portion or all 50 of the reaction products instead of being charged into the separator may be recirculated through the by-pass line 79 and the line 80 containing pump 81 to the alkylation operation. The acid 55 separating out in the separator 78 may be withdrawn from the system through the valve controlled line 82. It is preferable, however, to recycle a portion or all of this acid to the alkylation operation through the lines 83 and 80.

56 The hydrocarbons settling out in the separator 78 are passed through the line 85 to a mixer 86 wherein they are intimately contacted with a neutralizing agent, such as an aqueous alkali, for example, dilute soda ash, introduced through the line 87 by the pump 88. The products are passed 61 from the mixer 86 through the line 89 to a separator 90 wherein the neutralizer separates from the hydrocarbons and may be withdrawn through the line 91 or recycled to the mixer 86 through the lines 92 and 87. The neutralized hydrocarbons are conducted from the separator 90 through the line 94 to a fractionator 95 wherein the normally liquid hydrocarbons are fractionated to 66 separate any low boiling normally gaseous hydrocarbons unsuitable for use as gasoline. These 70 normally gaseous hydrocarbons are discharged 75

from the top of the fractionator through the valve controlled line 95. The liquid hydrocarbon fraction is withdrawn from the lower portion of the fractionator through the line 97 and discharged into a secondary fractionator 98 wherein the liquids are fractionally distilled to separate, as a liquid residue, the high boiling liquids or bottoms, of higher boiling range than gasoline, which are withdrawn from the lower portion of the fractionator through the valve controlled line 100. The vapors containing the gasoline are conducted overhead through the vapor line 101 to a condenser 102 wherein the vapors are condensed and the condensate passed through the run-down line 103 to an accumulator 104.

While only one alkylation unit is shown for the treatment of the various olefinic polymers from the separate stages of polymerization, it is contemplated that any number of alkylation units may be used, for example one for each polymer fraction. Multiple injection of the olefins or polymers into two or more of the alkylation tanks may be used to improve the yield and quality of the product. It is to be understood that various mixtures of the separate polymers may be utilized, if desired, as a charging stock to the alkylation operation. Moreover, if desired, the separate polymers may be blended as desired and the blend utilized as a charging stock to the alkylation operation.

The alkylation operation is preferably carried out in the liquid phase which may be obtained by applying sufficient pressure, for example about 25 to 150 pounds, to maintain the products in the liquid phase. The temperatures ordinarily employed range from about zero to 125° F., preferably about 60 to 90° F. If the various polymers are alkylated separately, the temperature and pressure conditions may be regulated to obtain optimum results, from the standpoint of yield and antiknock value.

In the foregoing description of the process of the invention, normally gaseous olefins are selectively polymerized in the vapor phase to obtain olefinic polymers which are in general normally liquid products. These normally liquid products are used in the alkylation of isoparaffins, such as isobutane, to obtain branch chain hydrocarbons within the gasoline boiling range and having a high antiknock value.

In the modification of the invention to be described hereinafter, normally gaseous olefin hydrocarbons are separated by absorption in sulfuric acid of the proper strength to selectively absorb the various olefins in the mixture; the olefins thus separated may be subjected to alkylation without polymerization thereof, although it is contemplated that the absorbed olefins may be polymerized, particularly the C₄ olefins, such as isobutylene. It is intended, however, to selectively absorb the olefins in the sulfuric acid and then use the acid mixture in the alkylation operation. In the case of olefins of lower molecular weight, strong acid is required in the absorption operation and the resulting acid mixture may be used with little difficulty in the subsequent alkylation operation since a relatively strong acid is also required in the alkylation step. In the case of higher molecular weight olefins, weaker acids are generally required and it may be desirable in these cases to polymerize the olefins and use the polymers, but the acid mixture may be used without the intermediate polymerization by building up the acid mixture to a strength suitable for alkylation.

Referring to Figure 2, the hydrocarbon charging stock may comprise a hydrocarbon mixture containing C₄ olefins, C₃ and C₄ olefins or C₂, C₃ and C₄ olefins, as well as various amounts of paraffins of the same molecular weight. This charging stock is introduced through the line 105 and forced by the pump 106 through the line 108 to a series of absorbers 110, 111 and 112, wherein the hydrocarbons in gaseous phase are contacted with acid introduced through the line 114 by the pump 115. The acid may be sulfuric acid of about 60 to 75% concentration and preferably about 65 to 66%. At a temperature of about 30° C. or below, the acid absorbs preferentially the isobutylene. The acid and hydrocarbons pass countercurrently through the absorber 110, the unabsorbed hydrocarbons passing out of the top of the absorber through the line 116 and into the lower portion of the absorber 111. The acid and absorbed hydrocarbons are conducted from the lower portion of the absorber 110 through the line 117 in which is located a pump 118 to the upper portion of the absorber 111. The acid and hydrocarbons recontacted in the absorber 111, the hydrocarbons passing from the top of the absorber 111 through the line 120 to the lower portion of the absorber 112, while the acid is pumped from the lower portion of the absorber 111 by the pump 121 through the line 122 to the upper portion of the absorber 112. While three absorbers are shown, it is contemplated that any number may be used to obtain the desired results. The unabsorbed hydrocarbons are released from the top of absorber 112 through the valve controlled line 124. Under the conditions specified, substantially all the isobutylene should be preferentially absorbed by the acid.

The acid mixture containing absorbed isobutylene is withdrawn from the bottom of absorber 112 through the line 125 and is forced by the pump 126 to an alkylation system referred to hereinafter. Any portion of the acid mixture may be withdrawn through the line 125 and may be recycled to the absorbers through the branch line 127 by the pump 128. The acid mixture from line 125 is introduced into an alkylation tank 130 wherein it is contacted with strong acid of suitable strength, for example 98 to 105%, in sufficient amount to raise the acidity of the mixture to about 94 to 96%. Such strong acid may be introduced through the line 131 in which is located a pump 132. The acid mixture in the vessel 130 is also contacted with an isoparaffin, such as isobutane, introduced through the line 134 and pump 135. Sufficient isobutene is added to bring the ratio of isobutane to olefins in the mixture to at least 1:1 and preferably about 3:1. The products are passed from the vessel 130 through the line 136 to a second alkylation tank 138. The reaction taking place in the alkylation tanks is essentially the alkylation of isobutane with isobutylene to form normally liquid hydrocarbons. While the nature of the reactions is not fully understood, it is believed that a reaction takes place between the isobutane and the acid hydrocarbon compounds, which may comprise alkyl sulfates, to produce branch chain hydrocarbons comprising a substantial amount of isooctane. The conditions maintained in the alkylation tanks are essentially the same as those described in connection with Figure 1.

The alkylation products pass from the last tank 138 through the line 144 to a separator 145. Any portion of this mixture from line 144 may be

recycled through the alkylation tanks by the line 147 and pump 148. In the separator 145 the acid settles out from the hydrocarbons in the lower portion thereof and may be withdrawn through the line 150 or recycled to the alkylation tanks through the lines 151 and 141. The hydrocarbons in the upper layer pass from the separator 145 through the line 152 to a mixer 153. An alkaline neutralizing reagent, such as soda ash solution, is introduced into the mixer 153 through the line 155 containing pump 156 to neutralize any acid in the oil. The mixture passes from the mixer through the line 157 to a separator 158. The alkaline solution separates from the oil in separator 158 and may be withdrawn from the system through the line 159 or recycled to the mixer 153 by the pump 160 through the line 161. The hydrocarbon layer separating in the separator 158 is withdrawn through the line 163 to a fractionator 164. In this fractionator the oil is distilled to separate the hydrocarbons of gasoline boiling point and lower as vapors, while the bottoms of higher boiling point than gasoline are withdrawn as bottoms from the lower portion of the fractionator, through the valve controlled line 165. The gasoline vapors pass overhead through the vapor line 167 to condenser coil 168 where the vapors are condensed and the resultant distillate passes through a rundown line 170 to a receiver 171.

The acid mixture withdrawn from the lower portion of absorber 112 through the line 125, according to one modification, may be passed through the branch line 174 to polymerization vessel 175. In this vessel the mixture is raised to sufficient temperature, for example about 180 to 200° F. by suitable heating, for example in steam coil 176. At this temperature the absorbed olefins, for example isobutylene, polymerizes chiefly to the dimer or di-isobutylene which separates as an oil layer and is withdrawn from the vessel 175 through the line 177 to a fractionator 178. The acid layer collecting in the vessel 175 may be withdrawn through the line 173. A portion or all of this acid may be returned through the branch line 179 and line 127 to the absorbers. In the fractionator the polymers are separated from lower boiling hydrocarbons, including unreacted isobutylene, as bottoms which are withdrawn from the lower portion of the fractionator through the line 180 which communicates with the line 125 leading to the mixer 130. The polymer may be subsequently treated as described heretofore with acid and isoparaffin to obtain high antiknock gasoline by alkylation. The overhead products from fractionator 178 are passed through the vapor line 181 and condenser 182 to a receiver 183. The products from the receiver 183 may be conducted through the line 184 to be subsequently treated as described hereinafter.

The hydrocarbons withdrawn through the line 124 from the top of the absorber 112, with or without those from receiver 183 are forced through the line 185 by the pump 186 to the first of a series of absorbers 188. These hydrocarbons should be substantially free from isobutylene and may comprise isomeric normal butenes, propylene and ethylene. In the absorbers the hydrocarbons are contacted with an acid introduced through the line 189 by the pump 190. The acid should be of sufficient strength, for example about 80% to 90% concentration and preferably about 85% to absorb the isomeric butenes. The products are conducted through a plurality of absorbers

188, 192 and 193 connected in series by the acid lines 195 and 196 and the hydrocarbon lines 197 and 198. The absorption of the isomeric butenes is effected in these absorbers at a temperature preferably not over 30° C. The acid mixture passes out of the last absorber 193 through the line 199 to a separator 200. Any portion of the acid mixture may be recycled through the absorbers by the line 201 in which is located pump 202. In the separator 200 a separation is made between the acid and hydrocarbon vapors, the latter passing out of the separator to the vapor line 204. The acid mixture containing the absorbed olefins is withdrawn from the separator through the line 205 and forced by the pump 206 through the line 207 to an alkylation tank 208. Any portion of this acid mixture may be recycled to the absorbers through the branch line 203 and the recycle line 201.

20 In the tank 208 the acid mixture is preferably fortified by a stronger acid in sufficient quantity to build the acidity up to about 95% or over. For this purpose a stronger acid, such as sulfuric acid of 98% strength or higher, is introduced through line 209 by the pump 210. There is also introduced into the tank 208 isobutane through the line 211 by pump 212 in sufficient amount to produce a ratio of isobutane to olefins of about 3:1. The resultant mixture is passed from the mixer 208 through the line 214 to a second alkylation tank 215. The tanks may be any suitable number, but are shown as the two tanks 215 and 208 connected in series by the line 214. The conditions maintained in these alkylation tanks are substantially the same as those described heretofore in connection with the tanks 130 and 138. It is intended to effect alkylation of the isobutane by the olefins to produce high antiknock gasoline hydrocarbons.

40 The reaction mixture is withdrawn from the tank 215 through the line 222 to a separator 223. A recycle line 224 containing pump 225 may be used for recycling any portion of the mixture in line 222 through the alkylation tanks. In the separator 223 the hydrocarbon alkylation products separate from the acid as a hydrocarbon layer which may be withdrawn through the line 227. The acid layer may be withdrawn from the bottom of the separator 223 through the line 228 and a portion or all of this acid may be recycled to the system through the branch line 229 and line 224. The hydrocarbons from the separator 223 pass through the line 227 to a mixer 230 wherein the hydrocarbons are contacted with a neutralizing agent, such as an aqueous alkali, for example dilute caustic alkali solution, introduced through the line 231 by the pump 232. The mixture is transferred from mixer 230 through the line 234 to a separator 235 wherein the neutralizing agent separates out and may be withdrawn through the line 236 or recycled to the mixer 230 through the line 237 by the pump 238. The neutralized hydrocarbons are conducted from the separator 235 through the line 240 to a fractionator 241. In the fractionator the hydrocarbons are subjected to fractional distillation to separate the higher boiling hydrocarbons as bottoms which are withdrawn through the line 242 while the lower boiling hydrocarbons comprising gasoline are removed overhead as vapors through the vapor line 243 and thence through the condenser coil 244 and run-down line 245 to an accumulator 246.

70 The hydrocarbon withdrawn from the separator 200 should be substantially free from C₄ olefins and may comprise propylene and ethylene, along

with various saturated hydrocarbons. These unreacted hydrocarbons are forced by the pump 250 through the line 251 to an absorber 252 wherein they are contacted with an acid, of sufficient strength to absorb the propylene, introduced through the line 253 by the pump 254. The acid should be at least 90% concentration, preferably about 94% or stronger. The mixture is conducted through a series of absorbers 252, 255 and 256, connected in series by acid lines 257 and 258, and the hydrocarbon lines 259 and 260. The temperature maintained in the absorbers is suitable for the absorption of propylene, preferably under 30° C. The products are conducted from the absorber 256 through the line 261 to a separator 262. Any portion of this acid mixture may be recycled by the pump 263 to the line 264. In the separator 262 the unabsorbed hydrocarbons separate and may be withdrawn through the valve controlled line 265. The acid and absorbed olefins are withdrawn from the lower portion of the separator through the line 267 and forced by the pump 268 through the line 269, to an alkylation tank 270. A branch line 272 is provided whereby any portion of the acid mixture from line 267 may be recycled to the absorbers, through the connecting line 264.

In the tank 270 the acid containing absorbed olefins is contacted with isobutane introduced through the line 271 by pump 273. The amount of isobutane introduced should be about three times that of the olefins contained in the acid mixture. The acid may be of sufficient strength to effect the intended alkylation of isobutane by the olefins. In case the acid, however, is of substantially lower concentration than 94%, it is desirable to introduce sufficient stronger acid through the line 274 by pump 275 in sufficient amount to bring the concentration of the acid mixture to 94% or above and preferably about 95 to 96%. This acid mixture is then conducted through the alkylation tanks 270 and 276 wherein the desired alkylation reaction takes place under substantially the same conditions as described heretofore. The alkylation products are conducted to the separator 278 although any portion thereof may be recycled through the line 279 by pump 280. In the separator 278, the acid is separated and withdrawn through the line 281 or recycled to the system through the lines 282 and 279. The hydrocarbons are conducted through the line 283 to a mixer 285 wherein they are contacted with a neutralizing agent, such as aqueous caustic soda, introduced through the line 286. The mixture is then transferred through the line 287 to a separator 288 wherein the neutralizing agent is separated and withdrawn through the line 289 or recycled through the line 290. The neutralized hydrocarbons are passed through the line 291 to a fractionator 292 wherein hydrocarbons are distilled to separate the gasoline fraction which is removed overhead through the vapor line 293 and condenser 294 to receiver 295, while the polymers higher boiling than gasoline are withdrawn from the bottom of the fractionator through the line 296.

The unreacted gases removed through the line 265 from separator 262 should be substantially free from olefins with the exception of ethylene. These hydrocarbons may be further treated to remove the ethylene by contacting the gases with concentrated acid, such as 94% or higher, at temperatures of about 80 to 90° C. and under high pressures, for example in excess of 450 pounds, and preferably about 800 pounds, whereby the

ethylene is absorbed. The acid containing the absorbed ethylene may be utilized for alkylating isoparaffins, under suitable conditions for alkylation. Such further treatment of the ethylene containing gases is not shown in the drawings.

As an example of the operation of the invention, unsaturated hydrocarbon gases from a cracking still, comprising essentially C₃ and C₄ hydrocarbons, were subjected to polymerization by contacting them with a phosphoric acid catalyst comprising a calcined mixture of pyro-phosphoric acid and kieselguhr. The temperature was about 100° F. and the pressure about 100 pounds. A polymer was separated comprising largely di-isobutylene. The unreacted gases were subjected to further polymerization in the presence of a similar catalyst, at temperatures of about 200° F. and 250 pounds pressure, whereby the isomeric butenes were polymerized and separated as a polymer. The three polymers were separately subjected to an alkylation reaction in the presence of isobutane and sulfuric acid of about 96% concentration. A gasoline fraction was separated from each of the polymerization products. The gasoline from the treatment of the di-isobutylene had an octane rating of about 92 and contained a substantial amount of iso-octane. The gasoline from the alkylation of the isomeric butene polymer had an octane rating of around 90 and also had a substantial iso-octane content. The gasoline obtained from the alkylation products utilizing the propylene polymer had an octane rating of about 85 and contained a substantial amount of iso-heptane.

As another example of the operation of the invention, a C₄ unsaturated hydrocarbon fraction derived from a cracking still was contacted with sulfuric acid of about 70% strength at a temperature of 30° C., whereby the isobutylene was absorbed. The acid mixture was fortified with strong acid of sufficient strength to bring the acidity up to about 95%. The resulting product was subjected to an alkylation operation in the presence of isobutane, whereby an alkylation product was produced in which gasoline was separated having an octane value of about 92 containing a large amount of iso-octane. The unreacted gases containing the isomeric normal butenes were contacted with sulfuric acid of about 85% strength at a temperature of about 30° C. to absorb the butenes. The mixture of acid and absorbed butenes was fortified with strong acid to bring the acidity up to about 95% and the resultant mixture subjected to alkylation in the presence of isobutane. A gasoline fraction was separated from the alkylation products having an octane number of about 90 and containing a substantial amount of iso-octane.

In operating the invention according to the procedure described in connection with Figure 2, it is to be understood that the spent acid from the alkylation operation may be utilized in the absorption stage. Also it is intended that the spent acid from a stage requiring a higher concentration of acid may be utilized in the absorption or alkylation stage in any other step of the process. For example, it is intended that the spent acid from the propylene stage may be used in the absorption or the alkylation stages of the isomeric butylene or the isobutylene.

In case undesirable polymers are formed in the absorption stages of the process, it is contemplated that any portion or all of these polymers may be separated from the acid mixture prior to alkylation thereof. This separation step is not shown in the drawings.

The absorption of the olefins in the acid may take place either in the liquid or vapor phase by adjusting the temperature and pressure conditions. The liquid phase, of course, will increase the surface of contact between the hydrocarbons and absorbent.

An advantage of the present invention is the alkylation of relatively pure olefins which often produce increased yields over those possible when treating the mixtures of olefins. Furthermore, it is possible to produce from the various olefins, different types of alkylation products, which are often desirable as special fuels or as blending agents to improve the antiknock and volatility characteristics of certain fuels.

The feature in the catalytic alkylation of an olefinic feed stock comprising a more reactive olefin and a less reactive olefin, involving the separation of the more reactive olefin from the feed stock, alkyllating the more reactive olefin with a less concentrated alkylation catalyst, alkyllating the less reactive olefin with a more concentrated alkylation catalyst, and supplying catalyst withdrawn from the less reactive olefin alkylation zone to the more reactive olefin alkylation zone to serve as the alkylation catalyst in the latter, is disclosed and claimed in applicant's divisional application, Serial No. 519,759, filed January 26, 1944. Likewise, the inventions involving separation of an olefin or various olefins by a catalytic polymerization step or steps, in combination with catalytic alkylation, are also disclosed and claimed in said divisional application, and in applicant's copending application, Serial No. 482,269, filed April 8, 1943.

Obviously many modifications and variations of the invention, as hereinbefore set forth, may be made without departing from the spirit and scope thereof, and therefore only such limitations should be imposed as are indicated in the appended claims.

I claim:

1. A process for the alkylation of isoparaffins with olefins, which comprises reacting the olefin with sulfuric acid to form an alkyl sulfuric acid compound, separating said acid compound and then reacting said compound in the presence of strong sulfuric acid with an isoparaffin to form a branch chain saturated hydrocarbon compound.

2. A process for the treatment of hydrocarbons containing propylene, which comprises absorbing the propylene in strong sulfuric acid of over 90% concentration, then treating the acid solution at temperatures not in excess of about 125° F. with additional strong acid and isobutane whereby the isobutane is alkyllated by the absorbed propylene to form saturated normally liquid hydrocarbons within the gasoline boiling range.

3. A process for the alkylation of isoparaffins with olefins comprising absorbing normally gaseous olefins in concentrated sulfuric acid and reacting an isoparaffin with the absorption mixture of olefins and concentrated sulfuric acid in the presence of concentrated sulfuric acid and under alkylation conditions of operation to effect alkylation of the isoparaffin with said olefins.

4. A process of alkyllating an isoparaffin which

comprises forming an alkyl ester of sulfuric acid, thereafter contacting and reacting said preformed alkyl sulfate with an isoparaffin in the presence of concentrated sulfuric acid and under alkylation conditions of operation to effect alkylation of the isoparaffin with said ester.

5. In a process involving alkylation of a saturated hydrocarbon with an olefin derived from a petroleum base feed stock, the improvement which comprises absorbing the olefin from the feed stock with sulfuric acid to produce an acid solution of the esterified olefin, separating the solution from the residual feed stock, and reacting the separated solution with an isoparaffin in the presence of concentrated sulfuric acid under alkylation conditions to form an alkylate.

6. A process for the alkylation of an isoparaffin with an olefin which comprises absorbing the olefin in sulfuric acid in one step, then alkyllating the absorbed olefin product in a second step with an isoparaffin in the presence of concentrated sulphuric acid under alkyllating conditions, and recycling acid from the alkylation step to the absorption step.

7. A process for the alkylation of an isoparaffin with an olefin which comprises reacting the olefin with an acid to form a corresponding alkyl ester, and then alkyllating the said alkyl ester with an isoparaffin in the presence of concentrated sulfuric acid under alkyllating conditions.

8. A process for the alkylation of an isoparaffin with an olefin, which comprises reacting the olefin with sulfuric acid to form a solution of a corresponding alkyl sulfate in the sulfuric acid and wherein the strength of the resulting acid is less than about 90% concentration, fortifying the acid solution to bring the acid concentration up to above 90%, and then alkyllating the fortified solution with an isoparaffin under alkyllating conditions to produce normally liquid hydrocarbons within the gasoline boiling range.

9. A process for the alkylation of a low boiling isoparaffin with a low boiling olefin utilizing an olefinic hydrocarbon fraction containing paraffinic hydrocarbons in addition to the olefin, which comprises passing the hydrocarbon fraction countercurrent to a mineral acid in an absorption zone to thereby absorb the olefin from the hydrocarbon fraction, removing unabsorbed hydrocarbons adjacent one end of the absorption zone and acid containing absorbed olefin adjacent the other end of the absorption zone, and alkyllating the absorbed olefin with a low boiling isoparaffin in the presence of concentrated sulfuric acid under alkyllating conditions.

10. A process of alkyllating an isoparaffin having less than 6 carbon atoms per molecule to make high anti-knock gasoline boiling hydrocarbons, which comprises reacting less concentrated sulfuric acid with an olefin which forms therewith an alkyl ester of said sulfuric acid, then alkyllating an isoparaffin having less than 6 carbon atoms per molecule with the resulting alkyl ester in a second zone in the presence of more concentrated sulfuric acid of alkylation strength effective to cause alkylation of the isoparaffin with the said alkyl ester.

11. In a process involving alkyllation of isobutane and a butylene, the improvement which comprises treating a petroleum base feed stock containing a butylene and isobutane with sulfuric acid to produce a sulfuric acid solution of esterified butylene, separating the solution from the residual feed stock, reacting the separated solution with a large excess of isobutane in the pres-

ence of concentrated sulfuric acid under alkylation conditions to form alkylate, separating the resulting spent acid from the said alkylation step, and returning the separated spent acid for admixture with additional feed stock in the absorption step.

12. A process for the alkylation of an isoparaffin with an olefin which comprises reacting the olefin with an acid to form a corresponding alkyl ester, and then alkylating an isoparaffin with said alkyl ester in the presence of a corresponding acid alkylation catalyst under alkylation conditions.

13. A process for the manufacture of substantially saturated gasoline hydrocarbons of high anti-knock value which comprises feeding an isoparaffin and an alkyl sulfate into a reaction zone, with the isoparaffin maintained in substantial molar excess of the alkyl sulfate, and reacting the isoparaffin with said alkyl sulfate in said zone in the presence of strong sulfuric acid under alkylation conditions to produce substantially saturated gasoline hydrocarbons.

14. In a process for the manufacture of gasoline hydrocarbons of high anti-knock value from an isoparaffin and an olefinic refinery fraction, the method which comprises absorbing the olefin from the refinery fraction with an acid to produce an acid solution of the esterified olefin, separating the solution from the residual unabsorbed refinery fraction, and reacting an isoparaffin with the separated esterified olefin in the presence of a corresponding acid alkylation catalyst under alkylation conditions.

15. The method in the alkylation of a low boiling isoparaffin with a low boiling olefin for the production of motor fuel hydrocarbons utilizing an olefinic feed stock containing a more reactive olefin and a less reactive olefin, which comprises treating the olefinic feed stock under conditions

to selectively remove the more reactive olefin, then treating the remaining feed stock with sulfuric acid of absorption strength for the less reactive olefin under conditions to react with the less reactive olefin to form the corresponding alkyl ester, alkylating the said alkyl ester with a low boiling isoparaffin in the presence of sulfuric acid of alkylation strength under alkylation conditions to produce substantially saturated hydrocarbons within the gasoline boiling range, and separating a substantially saturated hydrocarbon fraction within the gasoline boiling range from said alkylation products.

ARTHUR R. GOLDSBY.
